(57) **CLAIM**

The ornamental design for a vehicle upper grille, as shown and described.

DESCRIPTION

FIG. 1 is a front perspective view of a vehicle upper grille showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view.

It will be understood that the broken lines shown in the drawings illustrate portions of the vehicle upper grille that form no part of claimed design.
